DEEP WELL PUMP

Benjamin F. Schmidt, Los Angeles, Calif.

Application November 28, 1944, Serial No. 565,470

6 Claims. (Cl. 103—46)

1

My invention relates to submersible pumps and has particular reference to an insert pump which is particularly adapted to the pumping of deep wells such as oil wells and the like.

In the oil producing art, it is common practice to use reciprocating pumps to pump oil to the ground surface from oil wells of great depth. These pumps are mounted deep within the well bore upon the lower end of a string of flow tubing through which the pumped oil is conveyed to the ground surface. Conventionally, a cylinder or barrel is attached, within which a piston or plunger is reciprocated by means of power transmitted from the ground surface through a string of reciprocating sucker rods.

This type of pumping equipment is inefficient and only a small fraction of the total energy put into the system is useful in lifting oil to the ground surface. In my copending application, Serial No. 548,518, filed August 8, 1944, now Patent No. 2,455,022 and entitled "Submersible double-acting fluid piston deep well pump," I have disclosed an electric motor driven fluid piston reciprocating insert pump which has been designed particularly to increase the overall efficiency of deep well pumps. The present invention is directed to a novel type of pumping unit which is particularly adapted for use in an assembly of the character disclosed in the aforementioned copending application.

It has for an object, the provision of a novel form of pulsator unit which is used to convert the rotating energy of the electric motor into reciprocating fluid energy for operating a fluid piston reciprocating pump.

It is an additional object of my invention to provide a novel form of pumping unit which may be used in place of the fluid piston reciprocating pump and which employs a series of pressure expandable elements such as bellows housed within a casing and which operate in conjunction with the usual inlet and outlet valves to raise the crude oil from the well bore to the ground surface.

It is an additional object of my invention to provide in a deep well pump of the character described hereinbefore a multi-unit diaphragm pumping assembly in which the expansion and contraction of the flexible diaphragms are employed to raise the crude oil to the ground surface.

It is a still further object of my invention to provide novel features of construction and a simple unitary assembly permitting various parts of the structure to be removed as a unit from

2

a single housing, thus facilitating maintenance and repair operations.

Other objects and advantages of my invention will become apparent from a study of the following specifications, read in connection with the accompanying drawings, wherein:

Fig. 1 is a side elevational view illustrating the general form and appearance of the preferred embodiment of my invention;

10 Fig. 2 is a longitudinal sectional view through the lower part of Fig. 1 and showing the details of construction of the pulsator element;

Fig. 3 is a cross sectional view taken substantially along the line III—III of Fig. 2;

15 Fig. 4 is a cross sectional view taken substantially along the line IV—IV of Fig. 2;

Fig. 5 is a longitudinal sectional view illustrating the details of construction of one form of pumping element, the form illustrated comprising 20 a fluid piston reciprocating pump;

Fig. 6 is a cross sectional view taken substantially along the line VI—VI of Fig. 5;

Fig. 7 is a cross sectional view taken substantially along the line VII—VII of Fig. 6;

25 Fig. 8 is a longitudinal sectional view similar to Fig. 5 but illustrating a modified form of pumping unit which employs pressure expandable elements for pumping the crude oil;

Fig. 9 is also a longitudinal sectional view similar to Fig. 5 but illustrating another modification of the invention employing a flexible diaphragm as a pumping element;

Fig. 10 is a cross sectional view taken substantially along the line X—X of Fig. 9;

30 Fig. 11 is a longitudinal sectional view illustrating a modified form of pulsator element which may be used in place of that illustrated in Fig. 2;

Fig. 12 is a cross sectional view taken substantially along the line XII—XII of Fig. 11; and

40 Fig. 13 is a cross sectional view taken substantially along the line XIII—XIII of Fig. 11.

Referring to the drawings, I have illustrated the preferred embodiment of my invention in Fig. 1 as comprising a pump housing 1 which is attached to the lower end of a string of flow tubing 2 as by means of a divided member 3 which provides for the introduction into the housing 1 of an armored electrical cable 4. The cable 4 is carried to the ground surface alongside of the flow tubing 2 and may be secured thereto at suitable intervals as by means of clamps or straps 5.

45 The electric cable 4 terminates in a junction box represented by the dotted rectangle 6 from which electrical connections extend to an elec-

tric motor driven unit 7 represented by the dotted line rectangle bearing that reference character. The rotating shaft of the electric motor 7 is coupled to a reduction gear unit represented by the dotted rectangle 8 in Fig. 1. A slow speed power take-off shaft of the reduction gear 8 is applied to the power input shaft of a pulsator unit represented by the dotted rectangle 9, by means of which the rotary power produced by the electric motor 8 is converted into a reciprocating fluid power which is used to operate a pumping assembly represented by the dotted rectangle 10 in Fig. 1 and which operates to lift crude oil admitted to the assembly through the inlet 11 to the ground surface through the member 3 and flow tubing 2.

By preference, the junction box 6, electric motor 7 and gear reduction 8 are constructed in accordance with the teachings contained in my aforementioned copending application. The present invention is directed particularly to the construction of the pulsator unit 9 and the secondary pumping unit 10.

Referring to Fig. 2, I have illustrated therein the pulsator unit 9 as being mounted within an interior housing 12. The housing 12 is preferably mounted concentrically within the outer housing 1 and held spaced therefrom by any suitable means so as to define between the housings 1 and 12 an annular space 13 through which crude oil is conveyed to the flow tubing 2. The inner housing 12 supports an upper pump body 14 which is disposed between an upper bearing member 15 and a lower bearing member 16. A central pump body 17 is positioned between the bearing member 16 and another bearing member 18.

Between the bearing member 18 and a bottom bearing member 19 there is positioned a lower pump assembly 20. The three assemblies and the four bearing members are secured to each other and to a lower closure 21 by means of a plurality of bolts or studs 22 passing longitudinally completely through the assembly. The lower closure 21 is secured to the inner housing 12 as by means of threads 23.

Each of the pump bodies 14 are identical and are longitudinally bored as indicated at 24 to receive a single crank shaft 25 which is journaled in each of the bearing members 15, 16, 18 and 19 as by means of ball bearings or other suitable anti-friction bearings 26. The upper end of the crank shaft 25 is suitably connected as by means of a coupling 27 to the slow speed power take-off shaft of the gear reduction unit 8. Each of the pump bodies 14 are provided with three laterally extending cylinder bores 28, 29 and 30, these bores being spaced circumferentially 120° and being spaced vertically a distance slightly exceeding their diameters.

Within each of the cylinder bores there is reciprocally mounted a piston 31 which is coupled by means of a wrist pin 32 to a connecting rod 33. Each of the three connecting rods 33 are rotatably mounted upon a single crank throw 34 as by means of needle or roller bearings 35 formed upon a split bushing as indicated in Fig. 3. The upper cylinder bores 28 of each of the pumping bodies 14, 17 and 20 are interconnected by longitudinally extending fluid passages 36. Corresponding passages 36 in each of the pump bodies are interconnected by means of apertures 37 provided in the intermediate bearing members 16 and 18. In a similar manner, the center cylinder

bore 29 of each of the pump bodies 14, 17 and 20 are interconnected by means of a longitudinally extending fluid passage 39 and a similar set of fluid passages 40 are used to interconnect the lower cylinder bores 30 of each of the pump bodies 14, 17 and 20.

It will be seen that the assembly just described constitutes a multi-piston pump in which three groups of three cylinders each are mounted at 120° with respect to the others. Each of the groups of three comprises one in each of the pump bodies 14, 17 and 20 and the pistons of each group are simultaneously operated. With this construction the crank throw 34 may be made the same for each of the three pump bodies as is clearly shown in Fig. 2. Journaling of the crank shaft 25 at the bearing members 16 and 18 is accomplished by forming an enlarged shaft portion 41 which is provided with a circular cross section disposed concentrically with respect to the axis of rotation of the shaft 25 and which is received within the inner race of a ball bearing 42.

The construction of each of the pump bodies 14, 17 and 20 may be simplified by forming each of the bodies from three identical sector-shaped parts 14a, 14b and 14c as shown in Fig. 3. It will be noted that three of the attaching bolts 22 are used so that one of each of the bolts passes through each of the sections 14a, 14b and 14c. Radial abutting faces 14d serve to hold the parts against circumferential movement relative to each other and a close fit between their exterior surface and the interior of the inner barrel 12 holds the parts against radial outward movement. Radial inward movement is prevented by the interaction of the abutting faces 14d.

As the crank shaft 25 is rotated, an operating fluid contained within the passages 36, 39 and 40 and in the cylinder bores connected thereto is reciprocated as the pistons are advanced and retracted within their respective cylinder bores. The reciprocation of the fluid thus effected is used to operate the pumping unit 10 which in turn operates to lift the crude oil to the ground surface.

I have shown in Fig. 5 as one form of pumping unit which may be used a fluid piston reciprocating pump. The unit shown therein comprises a pump body 43 which is centrally bored as shown at 44 to receive crude oil admitted through an inlet opening 45 past a ball check valve 46 mounted within a lower support 47 and resting upon a valve seat 48. Symmetrically disposed about the central bore 44 there are provided three pairs of longitudinally extending bores identified in Fig. 7 by the reference characters 49a-49b, 50a-50b and 51a-51b. These six bores comprise a three cylinder fluid piston reciprocating pump and each pair is respectively associated with the corresponding fluid passages 36, 39 and 40 previously described.

The connection between these passages and the bores 49a, 50a and 51a is effected by means of suitable passages 52, 53 and 54 (Fig. 4) formed in the closure member 21 above described and an upper head member 55 which serves to close the upper ends of the bores 49, 50 and 51 and which is secured to the lower closure member 21 as by means of bolts 56. The upper head member 55 serves as a housing for three identical inlet valves, one of which is shown at 57 in Fig. 5.

It will be noted that the upper head member 55 is provided with three angularly disposed bores 58, each of which receives a valve seat 59 upon

which the valve 51 rests. The discharge side of the valve 51 is communicated by a laterally extending passage 60 with an axially extending passage 61 aligned with and communicating with the cylinder bore 51b. A similar intercommunication is effected between the central bore 44 and the cylinder bores 49b and 50b.

The passages 61 each extend upwardly through the upper closure 55 and receive valve seats 62 upon which are rested outlet valves 63. The discharge side of the outlet valves 63 are communicated by means of laterally extending ports 64 with the annular space 13 positioned between the inner housing 12 and the outer housing 1.

The lower ends of the cylinder bores 49a and 49b are interconnected by means of a transversely extending channel 65. Similar channels 66 and 67 interconnect the lower ends of the bores 50a—50b and 51a—51b. Within each of the pairs of cylinder bores 49, 50 and 51 there is placed a quantity of mercury or other suitably heavy fluid 68 insoluble in the oil to be pumped sufficient to substantially fill one of the cylinder bores of each pair. Normally each of the bores of a given pair will be filled substantially half full due to the liquid in the interconnected bores seeking equivalent levels. The remaining half of bores 49a, 50a and 51a are each filled with operating fluid which is reciprocated by the operation of the pulsator unit 9.

In operation, as the pulsator assembly 9 is operated (the entire fluid system of the assembly 9 being filled with operating fluid) fluid is first forced downwardly through one of the longitudinally extending fluid passages, as for example the passage 36. The fluid being communicated with the bores 49a, exerts a downward pressure upon the mercury in that bore and displaces the same downwardly, causing a corresponding rise in the mercury in the associated bore 49b. As the mercury in bore 49b rises, any crude oil which may be contained within the bore 49b above the mercury will be forced upwardly through the passage 61 and past the discharge valve 63 and into the annular space 13, flow through the passage 58 into the central bore 44 being prevented by the inlet valve 57.

This operation reverses as soon as the pistons of the pulsator 9 have completed their stroke. As they are withdrawn, the flow of fluid in the passage 36 is reversed, causing the mercury to rise in the bore 49 and subside in the bore 49b. The low pressure thus produced above the mercury in the bore 49b raises crude oil through the inlet 45, past the foot valve 46 and upwardly through the central bore 44 to be admitted past the inlet valve 57 and into the upper part of the bore 49b through the passages 60 and 61, reverse flow of fluid from the annular space 13 through the passage 61 being at this time prevented by the closed discharge valve 63.

During the time the cylinder 49a—49b is performing the above described operation, the cylinders 50 and 51 are performing similar operations but are displaced in time phase by an amount equal to 120° of rotation of the crank shaft 25. Each, however, draws crude oil from the central bore 44 and discharges it into the annular space 13. By using the three cylinder arrangement described, a substantially continuous flow of fluid is maintained within the annular space 13 and avoids the disadvantageous effects of hydraulic hammer resulting from the repeated starting and stopping of fluid flow so characteristic of ordinary reciprocating pumps.

Attention is also directed to the fact that the pulsator assembly 9 is in effect a hydraulic transmission serving to transform the rotating energy of the electric motor into reciprocating fluid energy which is directly used to pump the crude oil. It will be noted that this arrangement eliminates the necessity of using inlet and outlet valves or distributing valves for controlling the fluid pumped by the pump assembly 9.

I have illustrated in Fig. 8 a modified form of pumping unit which may be used in place of the assembly shown in Fig. 5. The pumping device shown in Fig. 8 comprises three identical pumping units 69, 70 and 71 mounted one above the other within the housing 1. Each of the units comprises a head member 72 which is mounted within the housing 1 upon an inner housing 73.

The inner housing 73 is spaced from the housing 1 to define an annular space 74 through which crude oil is pumped to the flow tubing 2. Within the inner housing 73 there is mounted a pump barrel 75. The barrel 75 is preferably eccentrically positioned with respect to the housing 14 to define at one side a relatively wide space within which tubing lines 76 may be placed. Within the barrel 75 there is placed a pressure expansible element or bellows 77, the interior of which is communicated by means of passages 78 and 79 with the passage 36 of the pulsator assembly 9. The bellows 77 are preferably formed of metal, although other suitably strong resilient material may be used if desired.

The space within the barrel 75 and the exterior of the bellows 77 is communicated by means of a passage 80 formed in an intermediate head member 72a with a tubing line 81. The tubing line 81 extends downwardly and into communication with an inlet passage 82 formed in the lower closure 47 and forming a continuation of the inlet passage 45, being connected to the discharge side of the foot valve 46. An inlet valve 83 is interposed in the passage 80 to prevent reverse flow of fluid therethrough.

The interior of the barrel 75 is also communicated with the annular space 74 by means of passages 84 and 85 within which is interposed a ball check discharge valve 86.

The unit 70 is similar to the unit 69 just described, except that the interior of the bellows 77 thereof is connected by means of a passage 87 formed in the closure 72a to the tubing line 76 which is in turn connected to the fluid passage 39 of the pulsator 9. Likewise an inlet tubing connected to the passage 82 is used to admit crude oil into the interior of the pump barrel forming a part of the unit 70. A similar arrangement is employed with respect to the unit 71 in that tubing lines are used to connect the fluid passage 40 of the pulsator 9 to the interior of the expansible element, whereas the space within the barrel and exterior of the pressure expansible element is suitably connected to the passage 82.

It will be seen that as the pulsator 9 is operated, the pressure expansible elements of each of the units 69, 70 and 71 will be alternately expanded and contracted so as to alternately increase and decrease the free space contained within the barrel 75, the expansion resulting from the pressure developed by the delivery of actuating fluid from the pulsator 9 and the contraction resulting from the sub-atmospheric pressure caused by the withdrawal of fluid from the bellows by the pulsator 9. This changing of the volume within the barrel 75 causes crude oil contained therein to be displaced through the

passages 84 and 85 into the annular space 74 and causes crude oil to be drawn through the passage 82, tubing 81 and the passage 80 into the interior of the barrel. Each of the units operates identically and simultaneously but are spaced apart in time phase an amount equal to 120° of rotation of the crank shaft 25.

I have illustrated in Figs. 9 and 10 another modification of my invention which is similar in many respects to the form of the invention shown in Fig. 8. The principal difference lies in the type of pressure expansible element which is employed. As regards the closure 72, the inner housing 73 and the pump barrels 75, the units shown in Figs. 9 and 10 are identical with those shown in Fig. 8. Likewise, each of the units comprising the assembly shown in Figs. 9 and 10 are similar to each other in the same way that the corresponding units of Fig. 8 were similar.

One of these units is shown in detail in Figs. 9 and 10 as comprising a body member 88 which is provided with a longitudinally extending groove 89. The groove 89 is communicated by means of a series of ports 90 and recesses 91 with a longitudinally extending passage 92 which is in turn directly connected to the passage 36 of the pulsator unit 9. Across the groove or recess 89 there is stretched a diaphragm 93 of flexible material such as synthetic rubber or other oil-resistant material. A cover member 94 grooved complementary to the body member 88 is secured to the body member 88 as by means of bolts 95 and serves to secure the diaphragm 93 in place and prevent over-expansion or rupture by limiting movement of the same. The cover member 94 is provided with a plurality of inlet openings 96 which are preferably sloped downwardly as shown in Fig. 9 to reduce to a minimum the possibility of the ports 96 becoming clogged with sand or other foreign material carried in with the crude oil.

As fluid is pumped into and out of the recess 89 through operation of the pulsator unit 9, the flexible diaphragm 93 will be moved from side to side from a first position lying substantially in contact with the surface of the recess formed in the cover 94 to an opposite position lying substantially in contact with the surface of the groove 89. By this means the free volume within the barrel 75 is alternately increased and reduced by an amount equal to the combined volumes of the groove or recess 89 and the corresponding recess formed in the cover member 94.

As the volume is increased, crude oil is admitted through an inlet valve similar to the valve 83 shown in Fig. 8. As the volume is decreased, the fluid displaced thereby is discharged into the annular space 74, past the discharge valve 86 similar to that shown in Fig. 8. Each of the three units of the assembly shown in Fig. 9 operates simultaneously but in time phase relation equal to the 120° spacing of the cylinders in the pulsator unit 9. In so operating, they function to maintain a substantially continuous flow of fluid in the annular space 74.

Referring to Fig. 11, I have illustrated therein a modified form of pulsator unit which may be used instead of the unit shown in Fig. 2. As in the form of the invention shown in Fig. 2, the inner housing 12 is mounted concentrically within the outer housing 1 and is used to support the mechanism comprising the pulsator element. This mechanism includes an upper bearing block 100 within which is journaled as by means of roller bearings 101 a main pump drive shaft 102

which is intended to be connected to the slow speed power take-off shaft of the gear reduction unit 8. The shaft 102 carries near its lower end a main drive gear 103 and the shaft 102 terminates in a stub shaft portion 104 journaled in a bearing block 105 as by means of roller bearings 106.

The main drive gear 103 meshes with three driven gears, one of which is shown at 107 in Fig. 11. The gears 107 are suitably secured to or formed integrally with longitudinally extending drive shafts 108, 109 and 110 which are spaced equidistant from the axis of rotation of the shaft 102 and circumferentially spaced 120° from each other.

Immediately below the bearing block 105 there is mounted a unitary pump mechanism consisting of a bearing block 111, a cylinder block 112 and a bearing block 113. The bearing blocks 111 and 113 journal as by means of roller bearings 114 and 115 a crank shaft 116. The crank shaft 116 is provided with a single crank throw 117 upon which is journaled as by means of connecting rod bushings 118 and 119 a pair of connecting rods 120 and 121. The connecting rods are attached as by means of wrist pins 122 to pistons 123 which are slidable within transversely extending cylinder bores 124 formed in the cylinder block 112. The two cylinder bores 124 which are formed in the block 112 are disposed at an angle of 120° to each other. The upper end of the crank shaft 116 carries a driven gear 125 which meshes with drive gears 126, 127 and 128 formed, respectively, on the drive shafts 108, 109 and 110.

Two other identical pump units (three in all) are mounted within the inner housing 12 and are arranged to be driven from the drive shafts 108, 109 and 110 in a manner identical to that just described. Each of the three cylinder block assemblies is rotated 120° with respect to the adjacent block so that the six piston and cylinder assemblies comprise three pairs, each displaced 120° from the other two. Like cylinders are connected by means of longitudinally extending passages 130 and these passages are brought through the upper head member 55 to communicate with the cylinder bores 49a, 50a and 51a previously described.

Attention is directed to the fact that each of the individual units consisting of the bearing blocks 111 and 113, the cylinder body 112 and the associated mechanism constitutes a single unit, permitting a main pulsator unit to be made up of as many of these individual units as may be desired, it only being required that the drive shafts 108, 109 and 110 be made of a length corresponding to the number of units included in the assembly.

It will be noted by reference to Fig. 11 that the parts are so arranged as to slide within the housing 112, permitting the entire assembly to be readily inserted and removed. When the parts are assembled as shown, they may be held in fixed positions as by means of longitudinally extending bolts or studs 131 which pass through all of the units and serve to hold the units against relative angular displacement as well as relative axial displacement.

The operation of the form of the invention just described is similar to the operation of the unit illustrated in Fig. 2 except that power to the lower units is not transmitted through a common crank shaft but is instead transmitted through the drive shafts 108, 109 and 110 to the individual crank shafts 116 of each of the sub-

assembly units. With this construction it is, therefore, possible to employ a greater number of the individual units than is possible with the arrangement shown in Fig. 2 because in said arrangement the torque required to drive the lower units must be transmitted through the crank shaft portions of the upper units, whereas in the form of the invention just described, the torques required are transmitted through a plurality of drive shafts instead of through a single crank shaft, and thus this form is adapted for use at extremely high pressures.

From the foregoing it will be observed that I have provided a novel pump assembly which is characterized by the use of a pulsator unit of a reciprocating character and acting as a hydraulic transmission to transform the rotary energy of an electric motor or other suitable power source into reciprocating fluid energy to operate the reciprocating pumping elements for raising the crude oil to the ground surface.

It will also be noted that I have shown three novel types of crude oil pumping assemblies, each of which operates to maintain a substantially continuous flow of pumped fluid and each of which avoids the disadvantages of conventional reciprocating pumps in that all sliding motions are eliminated, no barrels and plungers are used to become scored or stick or leak because of sand, grit or other foreign material in the pumped fluid.

While I have shown and described the preferred embodiment of my invention, I do not desire to be limited to any of the details of construction shown or described herein, except as defined in the appended claims.

I claim:

1. A deep well submersible oil well pump comprising a prime mover, at least three piston pulsators actuated by the prime mover and having different cycles, means defining a plurality of pump chambers corresponding in number to the piston pulsators, an expandible member disposed within each pump chamber, valved inlets and outlets for each pump chamber for pumped fluid, and conduit means independently connecting each pulsator to the interior of a separate one of said expandible members, characterized by an absence of valves or other restrictions, whereby the interior of each expandible member and the conduit associated therewith may be filled with a power transmitting fluid so that the expandible members will enlarge in response to a piston pressure on the fluid to give a pumping action in each chamber and will contract when the fluid pressure is relieved by the piston.

2. A deep well submersible oil well pump comprising a prime mover, a plurality of piston pulsators actuated in synchronism and in phase by said prime mover, means defining a pump chamber, an expandible member disposed within said chamber, valved inlets and outlets for said chamber for pumped fluid, and conduit means connecting the interior of said expandible member with all of said pulsators, whereby the interior of said expandible member and said conduit means may be filled with a power transmission fluid to expand and contract said expandible member in response to pulsating pressure produced by said pulsator.

3. A submersible oil well pump comprising an elongated housing adapted to be lowered into the well bore and attached to the lower end of a string of oil flow tubing, said housing enclosing a prime mover, a plurality of piston pulsators disposed one above the other in said housing actuated in

synchronism and in phase by said prime mover, means defining an elongated pump chamber, an expandible member disposed within said chamber, valved inlets and outlets for said chamber for pumped fluid, and conduit means connecting the interior of said expandible member with all of said pulsators, said conduit means being characterized by an absence of valves or other restrictions, whereby the interior of said expandible member and said conduit means may be filled with a power transmission fluid to expand and contract said expandible member in response to pulsating pressure produced by said pulsator.

4. A submersible oil well pump comprising an elongated housing adapted to be lowered into the well bore and attached to the lower end of a string of oil flow tubing, said housing enclosing a prime mover, at least three piston pulsators, means connecting said piston pulsators to said prime mover for synchronous actuation but spaced in phase by a fraction of a full cycle equal to the reciprocal of the number of said pulsators, means defining a plurality of pump chambers corresponding in number to the piston pulsators and arranged one above the other in said elongated housing, an expandible member disposed within each pump chamber, valved inlets and outlets for each pump chamber for pumped fluid, said outlets all being connected to said flow tubing, and conduit means independently connecting each pulsator to the interior of a separate one of said expandible members, characterized by an absence of valves or other restrictions, whereby the interior of each expandible member and the conduit associated therewith may be filled with a power transmitting fluid so that the expandible members will enlarge and contract in overlapping succession in response to alternating piston pressure on the power fluid to give a pumping action in each chamber and produce a continuous flow of pumped fluid in said flow tubing.

5. A submersible oil well pump comprising an elongated housing adapted to be lowered into the well bore and attached to the lower end of a string of oil flow tubing, said housing enclosing a prime mover, a plurality of sets of piston pulsators, each set comprising at least three of said pulsators, said sets being arranged one above the other in said elongated housing, means connecting said piston pulsators to said prime mover for synchronous operation with corresponding pulsators in all of said sets operating in phase and with the pulsators within each set displaced in operating phase by a fraction of a full cycle equal to the reciprocal of the number of pulsators in each set, means defining a plurality of pump chambers corresponding in number to the piston pulsators in each set and arranged one above the other in said elongated housing, an expandible member disposed within each pump chamber, valved inlets and outlets for each pump chamber for pumped fluid, said outlets all being connected to said flow tubing, and a conduit for each expandible member, each of said conduits interconnecting corresponding piston pulsators in each set and connecting the interconnected pulsators to the interior of the corresponding expandible member, said conduit means being characterized by an absence of valves or other restrictions, whereby the interior of each expandible member and the conduit associated therewith may be filled with a power transmitting fluid so that the expandible members will enlarge and contract in overlapping succession in response to alter-

11

nating piston pressure on the fluid to give a pumping action in each chamber and produce a continuous flow of pumped fluid in said flow tubing.

6. In a multiple-acting submersible oil well pump mechanism; a housing supporting said mechanism; a tubular member connected to said housing having valve-controlled intake and discharge ports for oil to be pumped; a plurality of flexible, contractile and expandable elements housed in said tubular member; and instrumentalities in said submersible pump housing for pulsating operating fluid under controlled pressure in and out of each of said elements to produce a substantially continuous pumping action.

BENJAMIN F. SCHMIDT.
